UNITED STATES PATENT OFFICE.

WILLIAM L. WELLER, JR., OF LOUISVILLE, KENTUCKY, ASSIGNOR TO THE TIME STOCK FEEDER COMPANY, OF SAME PLACE.

TIME RELEASING DEVICE FOR GRAVITY-DOORS.

SPECIFICATION forming part of Letters Patent No. 505,415, dated September 19, 1893.

Application filed February 13, 1893. Serial No. 462,212. (No model.)

To all whom it may concern:

Be it known that I, WILLIAM L. WELLER, Jr., of Louisville, in the county of Jefferson and State of Kentucky, have invented new and useful Improvements in Automatic Releasing Devices for Gravity-Doors, of which the following, taken in connection with the accompanying drawings, is a full, clear, and exact description.

This invention relates to improved means for operating gravity doors intended to be used in connection with an automatic stock-feeder, and is applicable to any device or apparatus in which it is desirable that the doors may be permitted to drop by gravity at certain predetermined times.

The invention consists in certain features of detail construction hereinafter more fully pointed out, and specifically referred to in the claims.

In the annexed drawings similar letters of reference denote corresponding parts in all the views, in which—

Figure 1 is an elevation of a stock-feeder to which my device is applied for purposes of illustration. Fig. 2 is a top plan view of the same. Fig. 3 is a longitudinal vertical section of the same, and Figs. 4 and 5 are detail views of the escapement devices intended to retain and release the doors at the predetermined times.

Referring to the drawings—A— is the end wall of a stable to which the invention is applied; —B— is the side wall; —C— is a gravity door suspended by means of the catch —6— and lug —5—.

Extending entirely across the width of the space to be occupied by the gravity doors is a rod —4— upon which I provide lugs —5—, which lugs are held on said rod by means of set-screws —5^a— passing through said lugs and bearing on the rod —4— to retain the lugs in position to coincide with the spring catches —6— secured to the inner side of the door —C— so that, as the doors —C— are raised to their proper elevation the spring catches will ride over the edge of the lug —5— and engage therewith, thus securing the door in its elevated position while the rod —4— retains the position shown in the drawings.

At the left of the stall shown in the drawings is secured an ordinary alarm clock which has projecting laterally from it a lever —12—, while an angular extension of said lever on its inner end is in position to fall into a slot —a— cut in the alarm dial of the clock when the said slot comes into coincidence with such angular extension.

The rod —4— is provided with an angular extension —7— which has a cord —8— secured to its free end, and said cord runs from thence to a weight —9— which is provided with a ring —10— which is adapted to fit over the free end of a lever —11— pivoted near its outer end where said weight is attached, and at the point where the weight hangs the said lever is provided with a slight excision to better adapt it to hold said lever in position.

The lever —11— is provided at its inner end with a cut-away portion —11^a— so as to adapt it to rest in proper position under the outer end of the lever —12— projecting from the clock —13—.

When the doors are in their elevated position the parts are in the position shown in the details of Figs. 4 and 5, in so far as relates to the securing devices and the tripping means.

The doors are held in an elevated position by the catch —6— engaging the lug —5— on the rod —4—. While the rod 4 is provided with an angular extension 4^a and a weight 4^b on said extension to counterbalance the weight of the doors hung on the lugs on said rod 4, thus preventing revolution of said rod 4 and release of the doors except at predetermined times when the weight 9 is released, the said weight 9 then being sufficient to overbalance the weight 4^b so as to turn the rod 4 on its axis and release the doors. All that is necessary to release the door —C— is to bring the slot —a— of the alarm disk of the clock into coincidence with the angular portion of the lever —12—, when the pressure upward on said lever —12— at its free end will force the inner end thereof to descend, the angular portion then passing into the slot —a—, whereupon the weight —9— will overbalance the weight of the inner portion of the lever —11—, causing said weight to drop by

gravity, at which time its full weight will be thrown onto the angular portion —7— of the rod —4— thereby causing said rod to turn on its axis, the weight —9— being considerably greater than the weight 4^b. Turning the rod —4— on its axis will cause the lugs —5— to be freed from engagement with the spring catches —6—, whereupon the doors —C— will be released and will fall by gravity to from their elevated position shown.

It will be apparent that the arrangement of the rod —4—, lugs —5— and spring catches —6— may be duplicated indefinitely, and by merely increasing the weight —4^b— to compensate for the increased weight of the added doors —C— the device may be used with a series of doors to any desired extent.

It will be observed that the lugs —5— are secured in position on the rod —4— by means of set-screws —5^a— so that they may be slipped onto the rod —4— from the end—as many as may be required—and set in any desired position to correspond to the location of the spring catches —6— on the doors.

25 The operation of my device is as follows: The clock-lever —12—, trip-lever —11—, weight —9— being set in the position shown in the detail at Fig. 4, the doors are then raised to their full elevation, where the spring-catches —6— will engage with the lug —5— on the rod —4—, at which time said rod is in position shown in Fig. 2, with the weight —4^b— and rod —4^a— horizontal with the top of the stalls, the weight acting as a counter-balance for the door —C—. The parts will remain in this position until at a predetermined time the slot —a— of the alarm disk of the clock, and the angular portion of the lever —12—, will come into coincidence, when 40 the parts will be tripped as before indicated and the doors —C— will be permitted to drop by gravity in their slides, thus exposing any part of the apparatus theretofore hid by said doors.

45 Having described my invention, what I claim as new, and desire to secure by Letters Patent, is—

1. In an apparatus of the described class, a gravity door, a spring catch on said door, a balanced rocker-bar sustained in an elevated position in proximity to said door, a lug on said rocker-bar to engage said spring-catch, and a cranked extension of said rocker-bar normally sustained by a balance weight at the opposite end of said rocker bar, all combined substantially as specified. 55

2. In an apparatus of the described class, a gravity door, a spring-catch on the inner face of the said door, a balanced rocker-bar suspended in proximity to said door at its top edge, adjustable lugs projecting laterally from said bar in proximity to said spring-catches, an angular extension of said rocking bar, a balance weight on said rocking bar, a second angular extension on the opposite end of said bar, a cord extending thence to a weight, as —9—, a pivoted lever carrying said weight at its shorter end, a clock lever, as —12—, projecting laterally from a clock an alarm clock, an alarm disk in said clock, and a slot in said alarm disk adapted to come into coincidence with an angular portion of said lever —12— at certain predetermined times, all combined substantially as specified. 7c

3. In an apparatus of the described class, 75 a balanced rocking-bar, a cranked extension of the same at one end, a weight on said cranked extension, a lug projecting laterally from said rocking-bar, a gravity spring, a door-catch on said door engaging said lug, a second cranked extension at the opposite end of said bar, an alarm clock, a clock-lever, as —12—, a balanced lever normally held in position by said clock-lever, a weight sustained by said balanced lever, and a cord connecting said weight and the cranked extension of said rocking-bar, all combined substantially as specified. 85

In testimony whereof I have hereunto set my hand this 8th day of February, 1893.

WILLIAM L. WELLER, JR.
